SHINGLED ROOFING

Herbert Abraham, New York, N. Y., assignor to
 The Ruberoid Co., New York, N. Y., a corpora-
 tion of New Jersey

Application May 13, 1952, Serial No. 287,504

4 Claims. (Cl. 108—7)

1

This invention relates to a shingled roofing formed of shingles of the kind commonly known as asphalt shingles consisting of a base of roofing felt impregnated and coated with bituminous compositions, and usually faced with mineral granules or the like.

My invention is intended to produce a roofing composed of individual shingles of the "reroof" type, that is shingles that are adapted to be applied over a previously laid roof to provide a new and attractive covering.

One object of the invention is to provide a shingled roofing in which although each shingle is applied with but a single fastener nevertheless as laid they are all secured at four points.

Another object is to produce a shingled roofing, of the reroof type, that is strongly resistant to wind of high velocity.

A further object is to provide a roofing that is economical in use of shingle material.

A still further object is to produce a roof covering of attractive appearance composed of hexagonal shaped exposure patterns.

Another object is to provide a roof covering of the character described formed of shingles that are self-aligning.

In applying the shingled roofing of the present invention I preferably use fasteners or clinchers of the kind shown and described in my Patent No. 2,570,626, of October 9, 1951.

In the accompanying drawings:

Fig. 1 is a plan view of one of the shingles employed to form the roofing;

Fig. 2 is a plan view showing the manner in which the shingles are applied and laid;

Fig. 3 is a transverse sectional view, taken on the line 3—3 of Fig. 2, showing the butt end of an overlapping shingle about to be secured on the fastener;

Fig. 4 is a similar view, taken on the line 4—4 of Fig. 2, showing the butt end of the overlapping shingle secured and clinched; and,

Fig. 5 is a plan view showing the manner of cutting the shingles from a web of roofing material without waste.

An individual shingle 10 of the form employed to provide the roof covering is shown in Fig. 1 of the drawing. Shingles of that form may be conveniently manufactured from a web of roofing material 11 of suitable width, without waste, by cutting the web along the lines indicated in Fig. 5.

The shingle 10 has parallel, horizontal upper and lower edges 12 and 13 of the same length, and oblique side edges 14—14, and 15—15, each of which slopes at an angle of 45° to the horizontal.

2

At each side corner of the shingle is an angular projection or tab, the tab at the right corner being designated by the numeral 16 and that at the left corner by the numeral 17. Each tab has a lower straight edge 18, 19, respectively, the two edges 18—19 being in horizontal alignment with each other. The outer side edge of each tab is formed by a continuation of the shingle edge 14 on the corresponding side. The length of the horizontal edge 18 or 19 of each tab, as the case may be, is the same as that of the upper and lower horizontal edges 12 and 13 of the shingle. In the preferred embodiment these lengths are all three and one-half inches.

15 The shingles are laid in courses, as shown in Fig. 2, with the tabs 16 and 17 of adjacent shingles in overlapping relation and with their horizontal edges 18 and 19, respectively, superposed in registration with each other. It will be seen, 20 therefore, that the tabs, among other things, serve to self-align the shingles in horizontal courses and in properly spaced relationship. This expedites the correct application of the shingles to the roof. As shown, the tab 17 of one shingle overlaps the tab 16 of an adjacent one, but that order may be reversed, depending upon whether the shingles are applied from left to right or from right to left.

25 The lower shank 20 of a double pointed fastener or clincher 21 is driven into the overlying tab 17 of each shingle to penetrate through the underlying tab 16 of the adjacent shingle, as well as through the upper end portion of a shingle of the next lower course, and the previously laid covering and into the roof deck or sheathing 22. For the sake of clarity, the previously laid covering is not shown in the drawings.

At this stage of application the upper shank 23 of the fastener remains erect as seen in Fig. 3. When the shingles of any one course have

30 been applied, those of the next course are similarly applied, the butt portion 24 of each upper shingle being pressed down on the fastener-shank 23 so that the latter will penetrate through the

35 butt portion in such position that its lower edge 13 will be aligned with the superposed edges 18 and 19 of the tabs of the underlying shingles. Thereupon the shank 23 is bent down as seen in Fig. 4, to clinch the butt of the shingle.

40 When the shingles are laid and applied in the manner illustrated and described each shingle will be held at four points, namely, at its two side corners, its upper and lower ends, although in applying them only one fastener per shingle is 45 used. For example, in applying adjacent shin-

gles of any course, such as shingles 10a and 10b, a single fastener is driven into the tab 17a of shingle 10a. The lower shank or point 20 of that fastener penetrates through the overlapped tab 16b of shingle 10b and through the upper portion of shingle 10c of the next lower course. The butt of shingle 10d of the next upper course is held by clinching the shank or point 23 of the fastener thereon.

In its preferred form the height of the shingle, between its upper and lower edges 12 and 13, is twenty-two inches, while its width, between the side edges 14 and 15, is eighteen inches. As previously noted the length of the edges 12, 13, 18, and 19, are each three and one-half inches.

With shingles of the present form and of these dimensions, laid with a two and one-half inch headlap, it requires only about one hundred thirty-nine and a half square feet of shingle material to cover a "square" of roof surface, using only about sixty-two shingles per "square." From this it will be evident to those skilled in the art that the shingle is very economical in material. Because of the fact that they are self-aligning they may be laid easily and expeditiously, and since each shingle requires that only a single fastener be driven into it to hold the shingle eventually at four points, it will be seen that application of the shingled roofing is very simple. When applied the roofing presents an attractive appearance of staggered hexagonal shaped exposure patterns. Moreover, it is to be noted, that as there are three thicknesses of material at the butt end of each shingle, to wit, the edges 13, 18, and 19 an increased shadow effect is produced, thereby enhancing the ornamental appearance of the roof.

What I claim is:

1. A shingled roofing comprising a plurality of shingles forming a covering of staggered hexagonal patterns, each shingle having parallel horizontal upper and lower edges, oblique side edges, and a tab at each side corner, said tabs having horizontal lower edges in alignment with each other, the length of each of said tab edges being the same as that of the upper and lower shingle edges, said shingles being laid in courses with the corner tabs of adjacent ones of a course overlapping each other with their lower edges in registration to align the shingles, the shingles of each next upper course each being laid with its butt overlying the lapped tabs of adjacent shingles of the course below and with its lower edge in registration with the lower edges of said tabs, each shingle being fastened with a double pointed fastener the lower point of which penetrates through the overlapped tabs and the upper portion of a shingle of the next lower course, and the protruding upper point of which fastener penetrates the butt of a shingle of the next upper course and is clinched thereon.

2. A shingled roofing comprising a plurality of

shingles forming a covering of staggered hexagonal patterns, each shingle having parallel horizontal upper and lower edges, oblique side edges, and a triangular tab at each side corner the outer edge of which is a continuation of the upper oblique edge on the same side of the shingle, each tab having a horizontal lower edge in alignment one with the other, the length of the horizontal edge of each tab being the same as that of the upper and lower horizontal shingle edges, said shingles being laid in courses with the corner tabs of adjacent ones of a course overlapping each other with their lower edges in registration to align the shingles, the shingles of each next upper course each being laid with its butt overlying the lapped tabs of adjacent shingles of the course below and with its lower edge in registration with the lower edges of said tabs, each shingle being fastened with a double pointed fastener the lower point of which penetrates through the overlapped tabs and the upper portion of a shingle of the next lower course, and the protruding upper point of which fastener penetrates the butt of a shingle of the next upper courses and is clinched thereon.

3. A shingled roofing comprising a plurality of shingles each having a horizontal lower edge, oblique side edges, and a tab at each side corner, said tabs having horizontal lower edges in alignment with each other, the length of each of said tab horizontal edges being the same as the length of the horizontal lower shingle edge, said shingles being laid in courses with the corner tabs of adjacent ones of a course overlapping each other with their lower edges in registration to align the shingles, the shingles of each next upper course each being laid with its butt overlying the lapped tabs of adjacent shingles of the course below and with its lower edge in registration with the lower edges of said tabs, each shingle being fastened with a double pointed fastener the lower point of which penetrates through the overlapped tabs and the upper portion of a shingle of the next lower course, and the protruding upper point of which fastener penetrates the butt of a shingle of the next upper course and is clinched thereon.

4. A roofing shingle having parallel horizontal upper and lower edges, oblique side edges of forty-five degree angularity, and a triangular tab at each side corner, the outer edge of each tab being a continuation of the upper oblique edge on the same side of the shingle, said tabs having horizontal lower edges in alignment with each other, the length of each of said tab horizontal edges being the same as that of the upper and the lower horizontal edges of the shingle.

HERBERT ABRAHAM.
